US00D948542S

(12) **United States Design Patent** (10) Patent No.: **US D948,542 S**
Yuan et al. (45) Date of Patent: **** Apr. 12, 2022**

(54) **DISPLAY SCREEN OR PORTION THEREOF WITH ANIMATED GRAPHICAL USER INTERFACE**

(71) Applicant: **BEIJING XIAOMI MOBILE SOFTWARE CO., LTD.**, Beijing (CN)

(72) Inventors: **Bo Yuan**, Beijing (CN); **Tianyu Lin**, Beijing (CN)

(73) Assignee: **BEIJING XIAOMI MOBILE SOFTWARE CO., LTD.**, Beijing (CN)

(**) Term: **15 Years**

(21) Appl. No.: **35/510,025**

(22) Filed: **Jun. 3, 2020**

(80) **Hague Agreement Data**

Int. Filing Date: **Jun. 3, 2020**

Int. Reg. No.: **DM/209497**

Int. Reg. Date: **Jun. 3, 2020**

Int. Reg. Pub. Date: **Aug. 7, 2020**

(30) **Foreign Application Priority Data**

Dec. 11, 2019 (CN) 201930692833.2

(57) **CLAIM**

The ornamental design for a display screen or portion thereof with animated graphical user interface, as shown and described.

DESCRIPTION

Display screen or portion thereof with animated graphical user interface

1.1 is a first image of a display screen or portion thereof with animated graphical user interface showing the first embodiment of our new design;

1.2 is a second image thereof;

1.3 is a third image thereof;

3.1 is a first image of a display or portion thereof with animated graphical user interface showing the second embodiment of the new design;

3.2 is a second image thereof;

3.3 is a third image thereof;

The process between which one image transitions to another forms no part of the claimed design; the broken lines showing the phone and the display screen or a portion thereof are for the purpose of illustrating environment and form no part of the claimed designs; the broken lines showing elements on the display screen illustrate portions of the graphical user interface and form no part of the claimed designs; the horizontal tonal shading broken lines in reproductions 1.2, 1.3, 3.2 and 3.3 form a part of the claimed design.

1 Claim, 6 Drawing Sheets
